UNITED STATES PATENT OFFICE.

Doc# 1,018,155

1,018,155. WEB-PERFORATING MECHANISM. JAMES BENOUGH, Niagara Falls, N. Y., assignor to The Carter-Crume Co., Limited, Niagara Falls, N. Y., a Corporation. Filed Oct. 5, 1908. Serial No. 456,158.

To all whom it may concern:

Be it known that I, JAMES BENOUGH, a citizen of the United States, residing at Niagara Falls, in the county of Niagara and State of New York, have invented certain new and useful Improvements in Web-Perforating Mechanism, of which the following is a full, clear, and exact description, such as will enable others skilled in the art to which it appertains to make and use the same.

This invention relates broadly to printing mechanism, and more particularly to mechanism adapted to perforate traveling webs.

One of the objects of the invention is to provide mechanism of the above character which will be effective in operation and in which the liability of tearing the webs will be reduced to a minimum.

Other objects will be in part obvious and in part pointed out hereinafter.

The invention accordingly consists in the features of construction, combinations of elements and arrangement of parts which will be exemplified in the construction herein-after set forth, and the scope of the application of which will be indicated in the following claims.

Referring now to the drawings, wherein is illustrated one of the various possible embodiments of my invention, Figure 1 is a view illustrating diagrammatically a portion of a printing press, showing my improved perforating mechanism; and Fig. 2 is a top plan view of portions of the cylinders which carry the perforating members.

Similar reference characters refer to similar parts throughout the two views.

Referring now to the drawings, 1 indicates the female portion of the perforating mechanism and comprises a cylinder provided with annular peripheral grooves 2 which lie side by side throughout its entire length, as clearly shown in Fig. 2. This cylinder is suitably driven by gearing on the outside of the frame of the machine. Coöperating with cylinder 1 is a plurality of similar cylinders shown at 3, 4, 5 and 6, each of which, in the present instance, is provided with segments 7 and 8, Fig. 2. One of these segments is securely fixed to the shaft 9, and the other is allowed to swing free thereon so that it may be adjusted to any desired position thereon and secured in position, as by means of set screws, one of which is shown at 10.

The perforator blade 11 or male portion of the perforator is held between two plates,

12 and 13, one of which is provided with dowel pins which receive the blade, suitable holes being provided in the blade to receive said pins. A slot is provided in the segments, into which plates 12 and 13, constituting the blade holder, are fitted, said holder being held in position by any desired means, in the present instances as by means of the taper pins.

In order to secure lateral adjustment for the perforator blade, the bearings in which the cylinders 3, 4, 5 and 6 run are fitted with adjusting screws 14 at both ends of their shafts. The cylinders which carry the perforating members are provided at the ends of their shafts with suitably driven gear wheels, not shown, which may be held in place by means of set screws, so that said cylinders can be readily adjusted to any desired position.

In the operation of the mechanism, the web, which is shown at 15, is fed to the perforating means, as by means of a pair of cylinders 16 and 17, whereupon the perforator blades of the several cylinders are carried into engagement therewith. It will accordingly be seen that I have provided mechanism well adapted to attain, among others, the several ends and objects set forth in a simple yet efficient manner. Since the perforating members work in longitudinally extending grooves all danger of breakage is entirely eliminated.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention, which, as a matter of language, might be said to fall therebetween.

Having described my invention, what I claim as new and desire to secure by Letters Patent is:

1. In printing mechanism, in combination, a cylinder provided with a plurality of annular grooves, a second cylinder arranged adjacent thereto, a segment carried by said second cylinder, and a member provided with a plurality of perforating points carried by said segment, said perforating points being adapted to enter said grooves during the rotation of said cylinders.

2. In printing mechanism, in combination, a cylinder provided with a plurality of annular grooves, a second cylinder arranged adjacent thereto, a circumferentially adjustable segment carried by said second

1018155

Pg # 2

cylinder, a member carried by said segment and provided with a plurality of perforating points adapted to enter said grooves during the rotation of said cylinders, and means for effecting a relative longitudinal adjustment between said cylinders.

In testimony whereof I affix my signature, in the presence of two witnesses,

JAMES BENGough.

Witnesses:

WALTER GREIG,

EDWARD KIRBY BATTLE.
